UNITED STATES PATENT OFFICE.

BYRON A. HUDSON, OF WOONSOCKET, RHODE ISLAND.

SNOW GUARD.

Application filed February 14, 1924. Serial No. 692,777.

To all whom it may concern:

Be it known that I, BYRON A. HUDSON, a citizen of the United States, residing at Woonsocket, in the county of Providence and State of Rhode Island, have invented 5 new and useful Improvements in Snow Guards, of which the following is a specification.

My present invention pertains to improved 10 snow guards and it contemplates the provision of a device through the medium of which the liability of snow gathering upon a roof and sliding off during the melting period will be effectually precluded thereby 15 preventing damage to property or injury to persons.

The invention further contemplates the provision of a simple and inexpensive construction of snow guard that is easy to apply 20 and retain on shingle roofs where the necessity for preventing wear of the guard by the elements is desirable.

The invention in all of its details will be fully understood from the following description and claims when the same are read 25 in connection with the drawings accompanying and forming part of this specification, in which:

Figure 1 is a perspective view of my novel 30 guard showing the same as applied on a shingle roof.

Figure 2 is a longitudinal sectional view of Figure 1.

Figure 3 is a top plan view of the guard 35 per se.

Similar numerals of reference designate corresponding parts in all the views of the drawings.

My novel guard is particularly adapted 40 for use in connection with lapped shingles 1 that are secured to each other by means of the fastening members 2 on their lapped ends. The shingles on their meeting edges are provided with a semi-circular aperture 45 3 to receive the storm nails 4.

My invention comprises the extremely thin body portion 5 having an aperture 5^a at one end and a longitudinal slot 7 and at the opposite end from the aperture 5^a the device 50 is provided with the loops 9 and 10, the former of which terminates in the prong 8 and the latter of which terminates in the prong 11. The extreme end of the loop terminates in the forwardly extending portion 55 12.

This guard is made preferably of wire and as before stated consists of a flat portion that is extremely thin and the body portion 5 may be of any length desired. When occasion arises for instance, to secure the guard 60 on a shingled roof other than that of the construction shown, a hook may be substituted at the point 5^a.

The use of the fastening means 2 is for the purpose of locking the shingles in place 65 and the said fastening means 2 secure the shingles to the roof. In laying the improved guard one of the storm nails 4 is inserted through the slot 7 and into the aperture 3 upside down and after the shingles are secured together and placed in position upon the roof the guard is adjusted along the storm nail permitting the slot 7 to ride over the head nail thereof and a fastening nail 6 is then driven into the roof support. The 75 next set of shingles may be easily laid over the flat end 5 of the guard and the entire guard with the exception of the loop portions thereof will be out of contact with the weather. The flat arrangement of body portion 80 5 not only permits of close fitting shingles but will add to the strength of the guard and at the same time prevent the loop from tipping over. Added strength can be given to the body portion by forming 85 corrugations on each side of the slot 7 and parallel therewith.

When desired, instead of providing the slot 7 a series of apertures may be used. In the ordinary construction of snow guard, 90 the shank portion is of such bulky nature that it necessitates spreading apart of the shingles thereby exposing the shingles and the guards to the elements.

I would distinctly have it understood that 95 the securing of the guard in the manner above outlined is not imperative as any mode that may assert itself is applicable in the laying of the guard in its proper position with respect to the shingles.

The device is extremely simple in construction and comprises practically but one element and therefore liability of breakage of the device is eliminated.

Having described my invention, what I 105 claim and desire to secure by Letters-Patent is:—

1. In a guard for the purpose set forth, the combination of a single piece of bendable material having a slot in the body thereof 110

and an aperture in rear of the slot; said material being provided with an upstanding loop that terminates in a portion that rests flat with respect to the body.

- 5 2. In a snow guard, a body portion, a slot formed therein, and also having an aperture in rear of the slot, and a loop formed by bending the forward end of the body upstanding to produce two loop shaped portions and a flat portion formed at the base

of the loop and resting in the same plane as the body portion.

In testimony whereof I have hereunto set my hand in presence of two subscribing witnesses.

BYRON A. HUDSON.
